UNITED STATES PATENT OFFICE

152,988

DESIGN FOR A MINE CAR TRUCK

Paul Laukus, Sr., North Huntingdon Township, Westmoreland County, Pa., assignor to Irwin Foundry and Mine Car Company, Irwin, Pa., a corporation of Pennsylvania

Application October 15, 1946, Serial No. 133,955

Term of patent 14 years

(Cl. D66—1)

To all whom it may concern:

Be it known that I, Paul Laukus, Sr., a citizen of the United States, residing at Penn Shaft, North Huntingdon Township, in the county of Westmoreland and State of Pennsylvania, have invented a new, original, and ornamental Design for Mine Car Trucks, of which the following is a specification, reference being had to the accompanying drawing, forming part thereof.

Fig. 1 is a front perspective view of a mine car truck embodying my new design.

Fig. 2 is a perspective view of the mine car truck showing the front, top and one side of the truck.

The characteristic features of my design reside in the portions shown by means of full lines in the drawing.

I claim:

The ornamental design for a mine car truck, as shown and described.

PAUL LAUKUS, Sr.
